UNITED STATES PATENT OFFICE.

GEORGE H. CHAPMAN, OF CHICAGO, ILLINOIS.

ELECTROPNEUMATIC ORGAN-VALVE.

1,302,511.

Specification of Letters Patent.

Patented May 6, 1919.

Application filed June 28, 1918. Serial No. 242,340.

To all whom it may concern:

Be it known that I, GEORGE H. CHAPMAN, a citizen of the United States, residing at Chicago, in the county of Cook and State 5 of Illinois, have invented certain new and useful Improvements in Electropneumatic Organ-Valves, of which the following is a specification.

This invention relates to electropneumatic 10 valves used in the construction of pipe organs and has reference more particularly to improvements in what are known as the magnet valves that are employed to supply and exhaust the channels of air passages 15 controlling the primary pneumatics and valves.

One object of the present invention is to 20 simplify and cheapen the structure of devices of this kind, which object is attained 25 chiefly by the provision of a valve casing, the main body of which is formed as a one-piece block that is attachable to the under or upper side of the wind or action box and contains the valve chamber, valve or armature, and lateral air supply and exhaust 30 passage, which block has heretofore been made in two or three mating sections secured together with interposed packing to prevent leakage.

35 Another object is to simplify and improve the construction in respect to the disposition of the magnet leads, so as to both eliminate the necessity of carrying the magnet wires through the walls of the wind or action box, as has heretofore usually been the practice, and also locate the terminal pin to which one end of the magnet winding is connected wholly outside the walls of the wind or action box, for which purposes the 40 terminal pin is mounted in the valve block with its magnet wire engaging end lying in a recess or pocket in the action box engaging 45 face of the block, which affords room for soldering one lead wire of the magnet coil to the pin so that the solder will not project beyond the said face of the block and interfere with the air-tight joint between the block and the action box.

Another object of the invention is to provide 50 an improved spacer between the core of the magnet and the valve disk or armature.

A still further object is to provide a valve 55 casing structure presenting a desirable combination of lightness and strength to support the magnet rigidly and capable of be-

ing readily molded or cast to the desired shape, for which purpose I make the main body of the block of one piece of bakelite or other material having similar properties, 60 and I combine therewith a metal insert block, preferably of brass, and formed with knurled edges to hold it rigidly in the bakelite in which metal insert is secured the core 65 of the magnet and through which is formed the inlet duct to the valve chamber. In order that my present invention may be readily understood by those skilled in the art, I have illustrated in the accompanying drawing a practical and preferred embodiment thereof, in which drawing—

Figure 1 is a cross-section view through a 70 wind or action box and magnet-operated valve, showing the magnet and valve proper in elevation;

Fig. 2 is a section on line 2—2 of Fig. 1;

Fig. 3 is a perspective detail of the metal 75 insert block; and

Fig. 4 is a bottom plan view of the valve casing block with the plug and valve proper 80 omitted.

Referring to the drawing, 1 designates the wind or action box of usual construction, the bottom wall of which is provided with ducts or passages 2 and 3, the former communicat- 85 ing at its upper end with the interior of the action box and accommodating an electromagnet 4, while the latter is channeled through the bottom of the action box so that it can supply and exhaust the air to and 90 from a primary pneumatic. Mounted in and extending lengthwise of the action box is a metal conducting rod or wire 6 to which one lead 7 of the winding of each of the several magnets is soldered. The parts thus far described are or may be all as usual in constructions of this kind.

Attached to the underside of the bottom wall of the action box by a pair of screws 8 and a gasket 9 is the valve housing or casing, 100 the main body 10 of which consists of a one-piece rectangular molded block, which is preferably made of bakelite,—a material excellently adapted to the purposes of an air valve housing or casing, in lieu of metal, on 105 account of its lightness, its resistance to chemical changes, as compared with metal, when exposed to certain gases, its imperviousness to moisture, and the fact that it is practically unaffected by atmospheric temperature changes. The block 10 is cored to 110 form a substantially central valve chamber

11, a lateral air duct 12 communicating with the chamber 11 and opening through the upper face of the block in register with the supply and exhaust duct 3, a recess or pocket 5 13 in its upper face and on the opposite side of the valve chamber from the air duct 12, and a threaded opening 14 through its lower face below the valve chamber.

In the upper face of the block 10 directly 10 over the valve chamber 11 is a metal insert 15, preferably of brass. The edges of this insert are knurled, or otherwise roughened, as shown at 15' in Fig. 3, and the same is very strongly and rigidly secured in place by 15 introducing it in the mold and casting the block 10 therearound. Through this metal insert block are formed a pair of holes 16 in which are set the pole-pieces 4' that form the core of the magnet 4. Between the holes 20 16 are formed a second pair of holes 17 that form an inlet duct from the passage 2 to the valve chamber 11. 18 designates a threaded plug preferably of the same material as the block 10 that normally fills the threaded 25 opening 14 in the bottom of the block and is made with a conical upper end 19 forming a valve-seat and with an axial outlet or vent duct 20. Within the valve chamber 11 is a metal disk valve or armature 21 that normally rests on the valve seat 19 and closes the outlet duct 20, but, when attracted by the magnet, opens the outlet duct 20 and closes the inlet ducts 17.

In the end of the block 10 opposite the air 30 duct 12 is mounted a terminal pin 22, said duct 12 is mounted a terminal pin 22, said pin being preferably introduced in the same manner as the insert 15 by casting the block therearound in the mold. The upper end of 35 this pin lies in the recess 13, and to it is soldered the other end 23 of the magnet winding; the recess serving to contain the solder below the upper face of the block 10 so that it does not impair the air-tight joint between the latter and the action box.

40 45 To the under side of the insert 15, which forms the top wall of the valve chamber 11, is cemented an annular washer 24 of paper or other thin material that serves as a spacer in the magnetic circuit and prevents 50 direct contact of the valve or armature with the core to avoid sticking due to residual magnetism. The valve disk is of sufficiently greater diameter than the internal diameter of the washer 24 to insure the closing of the 55 inlet duct 17 when the valve is raised by the magnet.

It is believed that the foregoing description, in connection with the drawing, will 60 make clear to those familiar with this art the structural novelties, mode of action, and advantages of this invention and the manner in which the stated objects are attained. Manifestly minor changes in structural details and relative arrangement of parts from those 65 here shown may be made without departing

from the substance of the invention or sacrificing any of the advantages secured thereby. Hence, I reserve such detail modifications and changes as fall within the spirit and purview of the appended claims.

70

I claim:

1. An electropneumatic organ valve, comprising a one-piece valve-casing block adapted to be attached to the outer surface of a wall of the action box and having a transverse bore forming the side walls of a valve chamber and a lateral air duct leading from said valve chamber to the face of the block which lies against said action box, a metal insert mounted in the same face of the block 75 and formed with an inlet duct to said valve chamber, an electro-magnet having its core mounted in said metal insert, a removable plug secured in the opposite face of said valve-casing block and formed with an outlet duct, and a valve in said valve chamber operated by said magnet to control said inlet and outlet ducts.

2. An electropneumatic organ valve, comprising a one-piece valve-casing adapted to be attached to the outer surface of a wall of the action box and having a transverse bore forming the side walls of a valve chamber, a lateral air duct leading from said valve chamber to the face of the block which lies 90 against said action box, and a threaded opening in its opposite face communicating with said valve chamber, a metal insert mounted in the action box engaging face of said block and forming one wall of said valve chamber, 100 said insert formed with an inlet duct to said valve chamber, an electro-magnet having its core mounted in said metal insert, a threaded plug mounted in said threaded opening and having a conical inner end forming a valve-seat and an axial outlet duct, and a disk valve in said valve chamber operated by 105 said magnet to control said inlet and outlet ducts.

3. In an electropneumatic organ valve, the combination of a valve-casing adapted to be attached to a wall of the wind chest and containing a valve chamber, an electro-magnet having its core set in a wall of said valve chamber, a disk valve in said valve chamber, and a thin annular washer cemented to the inner side of said valve-chamber wall and serving as a spacer to prevent direct contact of said valve with said core when the core is magnetized.

4. In an electropneumatic organ valve, the combination of a valve-casing block adapted to be attached to the outer side of a wall of the action box and formed with a recess in its action box engaging side, a terminal pin 125 mounted in said block with one end thereof lying in said recess, and an electro-magnet mounted in said block and having one end of its winding soldered to the end of said pin in said recess.

130

5. In an electropneumatic organ valve, the combination of a molded valve-casing block adapted to be attached to the outer side of a wall of the action box and formed with a 5 substantially central valve chamber, an air duct at one side of said valve chamber, and a recess in its action box engaging face located on the opposite side of said valve chamber from said air duct, a terminal pin 10 cast in said block with one end lying in said recess, and an electro-magnet mounted in said block and having one end of its winding soldered to the end of said pin in said recess.

6. As a new article of manufacture, a 15 valve casing for electropneumatic organ valves designed to be attached to the wall of the action box comprising a one piece block having a transverse bore forming the side walls of a valve chamber, an oblique passage 20 leading from said chamber through the side of said casing adapted to lie in contact with said wall of the action box, and a plugged opening leading from said chamber through the side of said casing adapted to lie remote 25 from the action box.

GEORGE H. CHAPMAN.
